(57) **CLAIM**

The ornamental design for a saw assembly base, as shown and described.

DESCRIPTION

FIG. 1 is a perspective view a saw assembly base showing our new design;

FIG. 2 is a top elevational view showing the design for the saw assembly base of FIG. 1;

FIG. 3 is a bottom elevational view showing the design for the saw assembly base of FIG. 1;

FIG. 4 is a front elevational view showing the design for the saw assembly base of FIG. 1;

FIG. 5 is a rear elevational view showing the design for the saw assembly base of FIG. 1;

FIG. 6 is a left side elevational view showing the design for the saw assembly base of FIG. 1; and,

FIG. 7 is a right side elevational view showing the design for the saw assembly base of FIG. 1.

In FIGS. 1-7, the broken lines showing of various items including (i) the saw assembly (FIGS. 1-7), (ii) the handle openings (FIGS. 1-3), (iii) the guide slot (FIGS. 1-3), (iv) the fence assembly (FIGS. 1-2 and 4-7), and (v) the feet (FIGS. 3-7) is for illustrative purposes only and forms no part of the claimed design.
